UNITED STATES PATENT OFFICE.

ABRAHAM BLUSTEIN, OF WASHINGTON, DISTRICT OF COLUMBIA.

BUCKLE FASTENER FOR WRIST-WATCH STRAPS, BRACELETS, AND THE LIKE.

Application filed December 6, 1928. Serial No. 324,283.

This invention relates to new and useful improvements in buckle devices to be used especially with wrist-watch straps or bracelets.

5 An object of the invention is to provide a simple but secure locking means on a foldable buckle for the purpose mentioned.

Another object is to make such a buckle of neat appearance, easy and economical to manufacture and, although securely locked when on the wearer's wrist, yet easy to lock and unlock during adjustment.

Another object is to make such a buckle of simple and durable construction without 15 sacrificing neatness of appearance.

Other objects will become apparent from the following description of the device illustrated in the drawing which is a part of this specification, and in which—

20 Fig. 1 is a view of the manner in which my buckle is intended to be used in connection with wrist-strap.

Fig. 2 is a plan view of the foldable buckle in its full extended position.

25 Fig. 3 is a side view in-section, showing the buckle of Fig. 2 in its folded and locked position.

Fig. 4 is a sectional view on plane 4—4 of Fig. 3.

30 Fig. 5 is a side view in-section of the modification of my buckle illustrated in plan in Fig. 7.

Figs. 6 and 7 are respectively a side and plan view of the modified form of buckle 35 fully open.

Fig. 8 is a detail in plan, of another modification.

In these figures, similar numerals will 40 designate similar parts throughout the drawing.

1 designates the clasp of the buckle. At one end of this clasp 1, there is attached one end of the strap 2 in any desired manner. My illustration shows the strap fastened adjustably by means of a pivoted clamping tongue. This tongue is shown pivoted at 4. It is a well known means for adjustably fastening a strap to a clasp and does not constitute a part of my invention. At the opposite end of the clasp there is pivotally secured at 5, the arcuate member 6 which is one of the foldable elements of my buckle. To the member 6 there is hingedly joined at 7 the arcuate member 8; the member 8 constituting the other foldable element of the buckle which has attached thereto the other

end of the wrist-strap 9. The strap may be of wire mesh or of any other flexible material such as leather or ribbon. It may constitute a part of a continuous bracelet or 60 it may carry midway between its ends a wrist-watch or some wrist ornament. In any case, the bracelet is a continuous but flexible loop, composed of the elements 1, 2, 9, and the folding elements 6 and 8, all joined end 65 to end. When the folding members 6 and 8 are in full open position, as shown in Figs. 2, 6 and 7, the bracelet can be slipped over the hand onto the wrist. When the bracelet is once on the wrist, its length is contracted 70 by the folding of the elements 6 and 8 one over the other and both beneath the strap, as shown in Figs. 3 and 5. In order to secure the bracelet or strap on the wrist, it must be locked by a suitable and safe means 75 which should keep the bracelet safe on the wrist and yet be easily operated when it is desired to remove the bracelet from the wrist.

For this purpose I provide what I believe to be a novel locking means, which consists in stamping out and bending up from the folding element 8, two tongues 10. These tongues when bent up are parallel to each other and to the axial line of the member 8. The edges of these tongues, which look 80 toward the hinged end of the member 8 are slightly undercut as shown at 11, so as to provide detents which hook up with and detain the other folding element 6, which is provided with two parallel slots designed 85 to cooperate with the hooks 10 for holding the folding members in locked position. The edges 13 of the slots 12 slip over the tongues 10, causing a slight compression and flexing of the member 6, while the said edges are 90 forced over the upper wide portion of the tongues 10 and the member 6 snaps locked by the said detents. The undercut locking edge 11 is made rounded off as clearly shown at 14, so that a firm pull will cause the unlocking of the folding members when the bracelet is to be removed by again flexing the member 6.

100 In my modified form shown in Fig. 6, I make the member 6 of an open or frame form so that a substantial portion of the member 8 is contained within the frame, and a substantial portion of both folding members lie flush. This construction eliminates bulkiness such as there is in the form shown 105 in Fig. 3 where the members 6 and 8 can not merge one within the other.

The modification of Fig. 8 is merely for economy of metal.

What I claim is:

1. In a wrist band, an extension device including two hinged foldable members made of sheet metal of equal thickness, one of said members having a substantial portion of its area cut out to form a rectangular open frame, and a substantial portion of the other of said members fitting within the frame of the first member whereby the opposite faces of said portion will be flush with the opposite faces of the sides of said open frame when the members are in folded position, and locking means for holding the said foldable members in folded position consisting of a plurality of undercut tongues formed in one of said members and a plurality of slots formed in the other member, each tongue cooperating with a corresponding slot in the other member.

2. In a wrist-band buckle, the combination of a pair of hingedly connected foldable members made of thin sheet metal of approximately the same thickness and joined as part of a bracelet, one of said members being of open frame formation and a substantial portion of the other of said members fitting within the frame whereby the opposite faces of said portion will lie flush with the opposite faces of the sides of said open frame when in folded position, and means for holding the said foldable members in locked position consisting of a plurality of undercut tongues formed in one of said members, and a plurality of slots formed in the other member, each tongue cooperating with a corresponding slot in the other member.

3. In an extension device including two

foldable thin sheet metal members shaped from sheet metal stock, a hinge connecting said members, one of said members being of frame form and the other member fitting within the frame whereby the opposite faces of said portion will lie flush with the opposite faces of the sides of said open frame when in folded position, and a cover member connected to one of the foldable members for covering that part of the two foldable members which overlap, and means for holding the said foldable members in locked position consisting of a plurality of undercut tongues formed in one of said foldable members, and a plurality of slots formed in the other foldable member, each tongue cooperating with a corresponding slot in the other member.

4. In a wrist band extension device, a plurality of foldable thin sheet metal members joined in a bracelet to increase the length thereof when in unfolded state, a rectangular member having a part thereof cut out to form an open frame shaped from sheet metal of light gauge, another member also shaped of sheet metal of the same gauge having a portion fitting into and lying flush with said open frame member when in folded position, and means for holding said foldable member in locked position, said means consisting of a plurality of undercut tongues of the same metal formed in one of said foldable members, and a plurality of elongated slots formed in the other member, each tongue cooperating with a corresponding slot in the other member.

In testimony whereof I affix my signature.

ABRAHAM BLUSTEIN.
